UNITED STATES PATENT OFFICE

163,142

EXPANSIBLE CHAIN

John F. Sand, Newark, N. J., assignor to Gemex Company, Union N. J., a corporation of New Jersey

Application January 19, 1951, Serial No. 13,873

Term of patent 7 years

(Cl. D45—4)

To all whom it may concern:

Be it known that I, John F. Sand, a citizen of the United States and a resident of Newark, Essex county, New Jersey, have invented a new, original, and ornamental Design for Expansible Chain, of which the following is a specification, reference being had to the accompanying drawing, forming part hereof, in which

Fig. 1 is a top plan view of an expansible chain embodying my new design;

Fig. 2 is a bottom plan view thereof;

Fig. 3 is an edge view;

Fig. 4 is a top plan view of the chain in an expanded position;

Fig. 5 is a perspective of one of the top links;

Fig. 6 is an edge view of one of the top links as viewed from line 6—6 or Fig. 1;

Fig. 7 is a section through a top link taken on line 7—7 of Fig. 1; and,

Fig. 8 is an enlarged section through a top link taken on line 8—8 of Fig. 6.

I claim:

The ornamental design for an expansible chain, as shown.

JOHN F. SAND.
